CHARLES J. KINDEL, OF GRAND RAPIDS, MICHIGAN, ASSIGNOR TO KINDEL FURNITURE COMPANY, OF GRAND RAPIDS, MICHIGAN, A CORPORATION OF MICHIGAN

FOLDING BED

Application filed September 25, 1928. Serial No. 308,226.

This invention relates to folding beds. It is an object and purpose of the present invention to provide a folding bed structure which in one position is extended into the form of a double bed and in its folded position is a couch or davenport. The invention consists in many novel details of construction and of arrangements and organizations of parts for providing a folding bed structure of the type stated, one which is quickly and easily changed from one position to the other, is of economical manufacturing construction and is effective to fulfill the purposes for which it is designed.

15 An understanding of the invention and the construction embodying the same may be had from the following description taken in connection with the accompanying drawings, in which,

20 Fig. 1 is a transverse vertical section through the folding bed in its folded position, the section being taken immediately inside one end of the bed.

Fig. 2 is a similar section showing the bed in the process of being turned to its unfolded position.

25 Fig. 3 is a like section with the bed in its completely unfolded position, and

30 Fig. 4 is a fragmentary, longitudinal, vertical section through one end of the bed when it is folded, as in Fig. 1.

Like reference characters refer to like parts in the different figures of the drawings.

In the construction of the bed two spaced apart ends are used including in each a front post 1 and a rear post 2 connected by an end board 3. The two ends are connected by front and rear horizontal rails 4 extending between the front posts 1 and rear posts 2 respectively, while a back 5, suitably upholstered, extends between the rear posts 2 at the upper portions thereof. Each end is completed as indicated at 6 by end frames which make the ends of the couch or davenport when the bed is in folded position.

At each end of the construction, substantially between the horizontal rails 4, and detachably connected to the posts 1 and 2 are supporting frames, each formed of two vertical angle bars 7 and two parallel horizontal

bars 8 permanently secured at their ends to the upper and lower ends of the angle bars 7. These frames are detachably secured to the posts 1 and 2, the outwardly extending legs of the angle bars 7 being diagonally slotted 55 upwardly and inwardly to connect with headed pins 9 (see Fig. 4) fastened to the inner sides of said posts 1 and 2. Substantially midway between the ends of the bars 8 a vertical bar 10 is located and connected at its ends to said bars 8, while back of the same and at the opposite side of the bars 8 a vertical post 11 is secured which extends above the frame and at its upper end is formed with an outturned lip 12, the purpose of which will later appear.

Two links 13 and 14 are pivotally connected at one end to each of the front posts 1 and the bars 10 as best shown in Figs. 2 and 3, and each of said links at its opposite end is turned at an obtuse angle making the extensions 15 and 16. Said links are pivotally connected to the ends of a horizontal frame 17 which lies between the end boards 3 and which is movable to different positions on 70 pivotal movements of the links 13 and 14. At the front side of the frame 17 and at each end thereof an upwardly extending post 18 is permanently secured which at its upper end is curved in a forward direction as 75 shown.

The frame 17 serves as a support for a spring and mattress construction. The spring construction includes the usual upper and lower wire frames 19 above the upper 85 one of which a mattress 20 is placed, while coiled springs 21 extend between and are secured at their ends to said frames 19. The mattress 20 is substantially twice the width of the frame 17 or the spring structure supported thereby, one-half of the mattress only being supported above the spring structure while the other half is otherwise supported as will be later described. The links 13 and 14 at each end of the bed are connected by 90 a horizontal bar 22 at a point beyond the pivotal connections of said links to the ends of said frame.

A second spring and mattress supporting frame 23 adjacent one side and at each end, 100

carries posts 24 which in the unfolded position of the bed, shown in Fig. 3, are located in front of the posts 18 and extend upwardly from the frame 23 and at their upper ends 5 are curved to the rear, being pivotally connected to the upper ends of the posts 18. This permits the frame 23 to be turned through 180° from a position where it lies over the frame 17, as in Fig. 1, to another 10 position where it lies in the same horizontal plane with the frame 17, as shown in Fig. 3.

The frame 23 is made of angle bars and carries an open wood frame 25 (see Fig. 4) 15 with which a spring and mattress and cushion structure is connected. The cushion cover 26 is fastened to the frame 25, extends therefrom and covers cushioning material 27 which is located over a plurality of coiled springs 28 extending from the cushion 27 20 through the frames 25 and 23 and connected at their other ends to a wire frame 29 to which the other half 30 of the mattress 20 is secured. The frame 25 with the cover 26, cushion 27 and spring structure 28 and 29 25 are readily assembled as a unit and then joined with the supported frame 23.

When the frame 23 is turned to its unfolded position, as shown in Fig. 3, the mattress sections 20 and 30 lie respectively over 30 the various spring structures carried by the frames 17 and 23 and the unfolded mattress is in a horizontal plane. On turning the frame 23 about the pivots connecting posts 18 and 24 to the position shown in Fig. 1 the 35 mattress sections 20 and 30 are folded upon each other and the cushion 27 is disposed between the ends of the davenport bed and is at the upper side whereby a spring supported cushion for a davenport or couch is 40 provided.

The bars 22 connecting links 13 and 14 are joined with the posts 24 by means of links 45 31, best shown in Fig. 3, which are pivotally connected at their ends to said bars and posts. An irregularly shaped bar 32 at one end has an arm 33 pivotally connected to each link 31 and at the opposite end has an arm 34 extending substantially in the same direction as the arm 33 which is pivotally 50 connected to a supported leg 35 at one end thereof. Said leg, a short distance from where it is pivotally connected to the arm 34, is pivotally connected between its ends to the end of the frame 33. When the bed is in unfolded position, as shown in Fig. 3, the irregularly shaped bar 32 at each end is in substantially inverted U-shaped position and the legs 35 extend downwardly from the frame 23 and rest upon the floor thereby supporting 55 the outer part of the frame 23 in the same horizontal plane with the frame 17.

The extensions 16 are bent at an angle from the links 14, one at each end of the bed, extend a distance beyond where they are pivotally connected to the bars 22. A coiled 60

tension spring 36 is secured at one end to the free end of each extension 16 and at its opposite end to a link bar 37 which in turn is connected with the U-shaped bar 32.

When the bed is in its unfolded position, 70 as shown in Fig. 3, the links 13 and 14 have been swung forwardly in a clockwise direction from a position below the horizontal to vertical position. The bars 22 lie directly over the ends of the frame 17 which furnish 75 stops against which said frame engages. The frame 17, with its superimposed spring and mattress structure, has been lifted from a lower position to an upper and somewhat forward position. The other spring and 80 mattress supported frame 23 lies in the horizontal plane with the frame 17 and is held in such position, being supported at one side by the depending posts 24 and at the outer side by the supporting legs 35. 85

On folding the bed the entire outer frame structure 23 with the attached bars 32 and legs 35 are turned about the pivots connecting the posts 18 and 24. The movement of the posts 24 through the connecting links 31 90 causes a longitudinal and downward movement of the bars 22 which actuates the links 13 and 14 to move pivotally in a reverse or counterclockwise direction, thereby lowering the entire structure to the position shown 95 in Fig. 1. Springs 36, under tension aid in the folding operation as the same partially counterbalance the weight of the frame 23 and the constructions attached thereto. In the fully folded position the frame 23 rests at 100 the rear on the lips 12 at the upper ends of posts 11 and at the front are supported by the posts 18 and 24 as shown in Fig. 1. The U-shaped bars 32 are also automatically 105 moved so as to swing the supporting legs 35 into horizontal position alongside the ends of the frame 33.

This construction has proved very practical and effective in service. It is readily and easily manufactured and assembled. The 110 invention is defined in the appended claims and is to be considered comprehensive of all forms of structure coming within the scope of said claims.

I claim:

1. In a construction of the class described, spaced apart vertical end supports, a pair of spaced apart links pivotally connected at one end to said supports, a horizontal frame to which said links are pivoted, a bar extending 120 between said links and pivotally connected thereto above the frame, a vertical post at the outer side and at each end of the frame having a forwardly extending portion at its upper end, a second frame adapted in one position to lie in the same horizontal plane with the first frame, posts extending at right angles from the second frame and rearwardly extending at their upper portions when the second frame is in horizontal position, 125 130

said posts on the second frame being pivotally connected to those on the first frame at their ends, spring structures carried by said frames adapted to carry a mattress over the same, 5 and connecting bars attached at one end to the second posts a short distance from their points of pivotal connection to the first posts and at their opposite ends having pivotal connection to said bars.

10 2. A construction containing the elements in combination defined in claim 1, combined with a U-shaped bar pivotally connected at one end to each of said connecting bars a short distance from where said connecting 15 bars are connected to said second posts, and supporting legs pivotally connected near one end, one to each side of the second frame and having pivotal connection to the other end of said U-shaped bars.

20 3. A construction containing the elements in combination defined in claim 1, combined with supporting legs pivotally connected at points between their ends, one to each end of the second mentioned frame, a U-shaped bar 25 pivotally connected at one end to each of said legs, said U-shaped bars at their opposite ends being pivotally connected to said connecting bars at points adjacent where the same are connected to said posts, springs connected to the free ends of the inner of said 30 links, and means connecting the opposite end of the springs to said U-shaped bars.

4. In a construction of the class described, spaced apart end supports, parallel links pivotally mounted at one end on said supports, a horizontal frame pivotally connected to and carried by said links, said links adjacent their upper ends having extensions disposed at an angle to the bodies of said links, a horizontal bar connecting said links above the frame, vertical posts extending upwardly one at each end and at the outer side of the frame, a second frame, posts extending at right angles therefrom at each end and pivotally connected at their outer ends to the ends of the first posts, and connecting bars pivotally connected at one end to the second posts a short distance from the points of pivotal connection of the same to the first mentioned posts and pivotally connected at their opposite ends to said bars between the ends thereof.

In testimony whereof I affix my signature.
CHARLES J. KINDEL.
